(57) **CLAIM**

We claim, the ornamental design for an electronic device, as shown and described.

DESCRIPTION

FIG. 1 is a perspective view of an electronic device, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another front view thereof, as shown in use;

FIG. 9 is another perspective view of the electronic device in an alternate configuration;

FIG. 10 is a front view thereof in the alternate configuration;

FIG. 11 is a rear view thereof in the alternate configuration;

FIG. 12 is a side view thereof in the alternate configuration;

FIG. 13 is another side view thereof in the alternate configuration;

FIG. 14 is a top view thereof in the alternate configuration; and,

FIG. 15 is a bottom view thereof in the alternate configuration.

The broken lines shown in the drawings illustrate portions of the electronic device that form no part of the claimed design.
